[57] CLAIM

The ornamental design for a head for a hand-held riveting tool, as shown and described.

DESCRIPTION

FIG. 1 is a front, top and one side perspective view of the head for a hand-held riveting tool showing a first embodiment of my new design;

FIG. 2 is a rear elevational view thereof;

FIG. 3 is an enlarged top plan view thereof;

FIG. 4 is an enlarged opposite side elevational view thereof;

FIG. 5 is a front, top and one side perspective view of the head for a hand-held riveting tool showing a second embodiment of my new design with the handle engaging portion thereof being shown in broken lines for ease of illustration only;

FIG. 6 is an enlarged rear elevational view thereof;

FIG. 7 is an enlarged top plan view thereof;

FIG. 8 is an enlarged opposite side elevational view thereof;

FIG. 9 is a front, top and one side perspective view of the head for a hand-held riveting tool showing a third embodiment of my new design with the handle engaging portion thereof being shown in broken lines for ease of illustration only;

FIG. 10 is an enlarged rear elevational view thereof;

FIG. 11 is an enlarged top plan view thereof;

FIG. 12 is an enlarged opposite side elevational view thereof.

The broken line showing the tool handles is for illustrative purposes only and forms no part of the claimed design.

Fig. 2
